(57) **CLAIM**

The ornamental design for a cup lid, as shown and described.

DESCRIPTION

FIG. 1 is a front, right and top perspective view of a cup lid, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof.

FIG. 9 is a front, right and top perspective view of the cup lid, shown in an open position of use; and,

FIG. 10 is a front, right and top perspective view of the cup lid, shown in a closed position of use, and further shown in use with an exemplary container.

The broken lines represent both parts of the article as well as environmental subject matter of an exemplary container. None of the broken lines form part of the claimed design.

1 Claim, 10 Drawing Sheets
